UNITED STATES PATENT OFFICE.

EARL W. CLARK, OF SHARON, PENNSYLVANIA.

FURNACE-SLAGGING APPARATUS.

1,329,293.

Specification of Letters Patent. Patented Jan. 27, 1920.

Application filed November 23, 1918. Serial No. 263,805.

To all whom it may concern:

Be it known that I, EARL W. CLARK, a citizen of the United States, residing at Sharon, in the county of Mercer and State

5 of Pennsylvania, have invented a certain new and useful Improvement in Furnace-Slagging Apparatus, of which the following is a full, clear, and exact description.

This invention relates to an apparatus for 10 slagging open hearth furnaces, and in certain respects is an improvement over the construction invented jointly by Frank C. Clark and myself and constituting the subject matter of our prior application, Serial 15 No. 202,118, filed November 15, 1917.

In the prior application referred to, there is disclosed a machine designed to slag furnaces, *i. e.*, to cover the bottom and banks of a furnace with slagging material such as 20 dolomite, so as to do away with the difficult hand slagging and to accomplish the slagging more quickly and more satisfactorily than is generally possible with the hand method.

25 In the prior application the results are attained by slagging apparatus movable along the line of the furnaces, for which purpose a regular furnace charging machine may be utilized, and provided with feeding and distributing means adapted to be inserted in the furnace, and including a discharge end or distributing member movable about in the furnace on a substantially vertical axis, in such a manner that slagging material 30 may be deposited over the floor and on the banks of the furnace.

The object of the present invention is to 40 provide certain improvements which increase the efficiency and utility of a machine of this character. More specifically considered, it is one of the principal objects of the invention to so mount the distributing member or part of the conveyer that it has a greater and different range of movement relative to the part which supports it, and particularly to so mount it that it can be swung about a horizontal axis as well as about a vertical axis so that the discharge end can be raised and lowered in addition to being 45 swung horizontally, thus admitting of a certain range of vertical movement irrespective

of the size of the furnace door opening through which is extended a part of the mechanism which feeds the slagging material.

55

Additionally the invention aims to provide other improved features including a distributor at the discharge end of the conveyer adapted to spread the material uniformly over the furnace floor.

60

The invention may be briefly summarized as consisting in certain novel details of construction and combination and arrangement of parts which will be described in the specification and set forth in the appended 65 claims.

In the accompanying sheets of drawings wherein I have shown several forms of my invention, Figure 1 is a side view of the principal parts of the apparatus utilized in 70 connection with a floor type charging machine, the furnace being shown in vertical section; Fig. 2 is a plan view of the same with the furnace in horizontal section; Fig. 3 is a similar view of the slagging apparatus 75 supported on a charging machine of the crane or overhead type; Fig. 4 is a horizontal sectional view of the same, the section being taken substantially along the irregular line 4—4 of Fig. 3; Fig. 5 is a sectional 80 view on an enlarged scale showing in detail a portion of the conveying and distributing means including the mounting and manner of shifting the distributing end thereof; Fig. 6 is a horizontal sectional view of a part 85 thereof; Fig. 7 is a view of the outer end of the distributing part of the conveyer showing a rotary distributor; Fig. 8 is a sectional view substantially along the line 8—8 of Fig. 7, omitting the screw conveyer; and 90 Fig. 9 is a transverse sectional view substantially along the line 9—9 of Fig. 4, looking in the direction indicated by the arrows.

In the drawings, 10 represents a furnace of the open hearth type which is to be 95 slagged by the apparatus constituting the subject matter of this invention, and a number of which are usually arranged in a row, and each having door openings 11, through which the furnace charge is inserted in the 100 normal operation of the furnace, and through which is inserted also that part of

the apparatus of the present invention which distributes the slagging material, usually dolomite, over the bottom and banks of the furnace in the manner illustrated at 5 12 in Figs. 1 and 3.

The furnace slagging apparatus as a whole, includes a suitable support and conveying portion capable of being moved about on the exterior of the furnaces, and from 10 furnace to furnace, and a portion or a part which is inserted into the furnace through the furnace door and is moved about therein so as to distribute the slagging material over the floor and banks of the furnace, the 15 slagging material being preferably fed from a source of supply on the exterior of the furnace to the discharging or distributing end. The conveying and supporting means or portion referred to above may be a permanent 20 part of the slagging apparatus, and may be used solely for that purpose, but as in the prior application already mentioned, I prefer to use as a part of the slagging apparatus a furnace charging machine to 25 support and convey about the mechanism or apparatus which feeds and distributes the slagging material, in which event the feeding and distributing portion is detachably connected to the peel of the furnace charging machine, and that manner of carrying 30 out my invention is illustrated in the drawings, which show the invention applied to or embodied in two different forms of furnace charging machines, neither of which 35 *per se* forms a part of the invention except in association with that part of the apparatus which performs the actual slagging operation.

In Fig. 1 I have shown my invention 40 applied to a floor type charging machine, which briefly considered, includes a wheeled frame or truck 13, adapted to run along the rails 14 of a track parallel to and in front of the line of furnaces. This frame 45 or truck has rails 15 which are at right angles to the rails 14 and support a wheeled carriage 16, movable toward and from a furnace. This carriage supports a peel housing 17, mounted to rock about a transverse or 50 horizontal axis 18, and in this housing there is a so-called peel 19 having a flanged forward end adapted in the normal operation of the machine to be detachably connected to one end of a box containing a charge 55 which is to be inserted into the furnace and dumped therein. The charging is done by first connecting the forward end of the peel to the box, then positioning the peel in line with the furnace, raising and lowering its 60 forward end until it is of the proper height with reference to the furnace door, running it and the charge-containing box into the door of the furnace, and then rotating the peel in its housing so as to empty the box, 65 after which the peel and the empty box are

retracted from the furnace, the inward and outward movements being obtained by shifting the carriage 17 forwardly and rearwardly over the track rails 15.

As will be subsequently explained, the 70 slagging part of the apparatus is connected to the forward end of the peel in the same manner that the charge-containing box is connected thereto, the forward end of the peel in both instances being inserted in a 75 groove of the part to be supported by the peel, in one case the box, and in the other case the slagging apparatus, which part is then locked to the peel by the forward end of a rod or bolt which extends centrally 80 through the peel and is controlled by the operator on the carriage. In the use of the slagging machine for my purpose, *i. e.* for slagging a furnace, the peel is not rotated in 85 the housing.

In Fig. 3 a charging machine of the crane or overhead type is illustrated. This machine includes an overhead crane or girder 20, adapted to be moved along overhead rails, one of which is shown at 21. This girder carries a transversely movable trolley or carriage 22, with a part extending downwardly therefrom to support the peel, and including an upper portion 23 and a lower portion 24 which can be turned about a vertical axis, 95 and having spaced vertical guides indicated at 25 in Fig. 3, accommodating the rollers of a vertically movable slide or member in the nature of a cross-head carrying at its lower end a horizontal platform 26, a peel 100 housing 27, and a peel 28, similar to the peel 19 of Fig. 1, and adapted to perform the same function as the latter.

The platform 26, housing 27 and peel 28 may be raised vertically in the guides 25 by 105 any suitable means such as a motor 29 on the trolley 22, and the carriage may be moved along the crane 20 by a motor such as shown at 30, and the lower part 24 including the peel may be turned about a vertical axis by 110 a motor 31. Additionally the peel may be turned about its own axis in the housing 27 by a motor 32, and the peel can be locked to or unlocked from the charge containing box by shifting a hand lever 33 on the platform 115 26, all these motors being controllable by the operator on the platform 26. Inasmuch as both the charging machines of Figs. 1 and 3 are standard and well known machines, further description or illustration of the 120 same is believed to be unnecessary.

It should be noted, however, that whereas the forward end of the peel 19 of Fig. 1 can be raised and lowered, and therefore properly positioned as to height with reference 125 to the furnace door, by rocking the peel housing about the horizontal axis, the peel 28 of Fig. 3 is bodily raised or lowered to properly position it as far as height is concerned with reference to the furnace door. 130

However, either type of charging machine can be utilized to support and manipulate the slagging apparatus, and either movement of the peel, whether the swinging 5 movement of Fig. 1, or the straight bodily vertical movement of Fig. 3, is adaptable to my invention.

The apparatus which is utilized with a conveying and supporting machine such as 10 either type of charging machine, includes a platform 34, on which is supported a hopper 35 adapted to be supplied with the slagging material. Likewise supported on the platform are actuating motors and driving 15 devices which will be referred to subsequently.

Additionally the apparatus includes mechanism for conveying the slagging material from the hopper and for distributing it about in the furnace. This includes in this 20 case, a hollow or tubular arm 36 containing a conveyer, preferably a screw conveyer 37, a portion of which is shown in Fig. 5. This screw conveyer extends along the bottom of the hopper so as to feed the material from 25 the hopper to the forward end of the tubular arm 36, and it consists preferably of a long sleeve having a spiral flange on its periphery and mounted on a shaft 38, supported at both ends.

30 At its outer end the tubular arm 36 has a head in the form of a casting 39, which is secured to, and forms a continuation of the arm 36. This casting, which, as shown most clearly in Fig. 6, is substantially circular 35 in outline, has a downwardly extending discharge tube 40 which is directly beneath the forward end of the screw conveyer 37, this tube discharging the slagging material to the distributing conveyer beneath. Be- 40 neath the head or casting 39 is a second head or casting 41, supported by the former through the medium of a flange 42 and ball bearings 43, so that the casting 41 may turn about a vertical axis coinciding with the 45 axis of the tube 40. Projecting from this head or casting 41 is a second hollow or tubular arm 44, the inner end of which is open at the top and directly beneath the tube 40 so as to receive the slagging material which 50 passes therefrom, and this second arm 44 contains a screw conveyer 45 mounted to rotate with a shaft 46 extending therethrough. At the outer end of the arm 44 there is a 55 distributor head 47 in which the outer end of the shaft 46 is journaled and having a discharge opening 48 through which the charging material is delivered to the floor or banks of the furnace.

It is in the construction and manner of 60 mounting and shifting the delivery part of the conveyer, *i. e.* the hollow arm 44 and the screw conveyer contained therein, that the chief part of the present invention is involved. A feature of importance of this new 65 construction is the fact that this delivery

part of the conveyer is capable not only of rotary movement about a vertical axis, which swings the discharge end in a circle, but also movement about a horizontal axis enabling the discharge end to be raised and 70 lowered relative to that part of the conveying means which is extended into the furnace, all of these movements being rendered possible without causing any interference 75 whatsoever with the operation of the screw conveyers. To the attainment of this end, the hollow arm 44 is not fixed to the rev- oluble casting 41, but has a forked inner end 49 pivoted at 50 to the casting 41. Ad- 80 ditionally I make the shaft 46 of the dis- tributing arm in two sections, there being at the inner end of the main part 46 which ex- tends through the arm 44 a relatively short section 51 journaled in the casting 41 for rotary movement only, and this section is 85 connected to the main section 46 by a uni- versal joint which will permit an oscilla- tory movement between the parts, the center of which (*i. e.* the center of movement) is on 90 the pivotal axis 50 of the hollow arm 44. 95 This universal joint is composed of a part 52 connected to the short shaft 51 and a companion part 53, which is connected with the main shaft 46. The arm 44 extends out- 95 wardly from the casting 41 through an open- ing which provides clearance enabling the arm 44 to be swung about the horizontal axis 50 so as to raise or lower the outer end of the arm 44.

I will next take up the mechanism by 100 which the screw conveyers are driven, and the means by which the delivery section of the conveyer may be swung horizontally or vertically. It will be observed by reference to Figs. 1 and 3, that the platform 34 which 105 is supported by the peel and its housing, and is always on the exterior of the furnace, is provided alongside of the hopper 35 with two motors 54 and 55. The motor 54 through reduction gearing 56 rotates a shaft 57 con- 110 nected by chain and sprocket gearing 58 to the outer end of the screw conveyer shaft 38 which extends through the hollow conveyer arm 36 projecting forwardly from the hop- per. At the forward end of the shaft 38 and 115 located in the head or casting 39 just be- yond the screw conveyer 37, is a bevel gear 59 which is rotated by the shaft 38, and ro- 120 tates a double bevel gear 60 surrounding and free to revolve about the discharge tube 40 leading from the upper conveyer arm 36 (see Fig. 4). This double bevel gear 60 drives a bevel gear 61 fixed to the part 52 of the universal joint connected to the short shaft 51 at the inner end of the lower or distribut- 125 ing conveyer shaft 46.

The second motor 55 through reduction gearing designated as a whole by the refer- ence character 62 and including gears rotat- 130 ing freely on the shaft 57, rotates a shaft

63 which is connected by chain and sprocket gearing 64 (see Fig. 9) to a shaft 65 which extends forwardly along the upper conveyer tubular arm 36 through a casing 66 which 5 may be cast integral with the arm 36. As shown in Fig. 6, the forward end of this shaft projects into the head or casting 39 in which it is journaled, and is provided at its forward end with a bevel gear 67, which 10 drives a bevel gear 68 and a second bevel gear 69, which latter meshes with a bevel gear 70 secured to the upper part of the lower head or casting 41 concentric with respect to the tube 40 about which the casting 15 41 is mounted to rotate.

Thus it will be seen that the motor 54 drives the upper screw conveyer 37, which in turn drives the lower screw conveyer 45, and that by operating the motor 55, which 20 is preferably a reversing motor, the lower swiveled head or casting 41 can be turned so as to swing the lower or distributing conveyer horizontally about a vertical axis or a substantially vertical axis.

25 The swinging of the hollow arm 44 of the lower or distributing conveyer about the horizontal axis to raise or lower the inner end of the arm may be taken advantage of in different ways without in any way interfering with the normal feeding operation, i. e. the movement of the screw conveyers or the horizontal swinging movement of the distributing part thereof. For example, I 30 may adjust the height of the outer discharge end of the arm 44, that is to say, I may adjust the angle of the axis of this arm with respect to the axis of the upper arm 36 on the outside of the furnace before the conveying and distributing mechanism is run 35 into the furnace to slag the same, in which event, all that is needed is the insertion of a block 71 of predetermined thickness, such as shown in Fig. 6, between the arm 44 and the portion of the casting 41 at or adjacent 40 the point where the arm projects from the casting. Or instead of relying upon a supporting block of selected thickness to cause the discharge end of the conveyer to be at a predetermined height in the furnace, I may 45 at will raise and lower the discharge end of the conveyer arm 44, and to this end I mount 50 on the platform 34 a winch drum 72 (see particularly Fig. 9) which can be either power operated or manually turned by a crank 73. This winch drum receives a rope or cable 74, which extends forwardly along the hollow conveyer arm 36 through guide openings 75, 76 and 77 (see Fig. 5) in the head or casting 39 at the outer end of arm 60 36, the guide opening 77 being in line with the axis about which the lower head or casting is swiveled to swing horizontally. Through this guide opening 77, the cable extends out through the top of the casting 65 39, and over an upstanding rounded bead 78,

which extends around the periphery at the top of the casting 39, and then the cable extends downwardly to the arm 44 to which it is attached near its outer end, as shown at 79 in Fig. 5.

70 Thus by this mechanism, including the winch drum and the cable, from a point outside of the furnace the discharge end of the distributing member of the conveyer can be raised or lowered without interfering with 75 the continuous operation of the conveyer and without affecting in any way the horizontal swinging movement of the arm 44 or the distributing part of the conveyer. In fact, the parts are so connected and driven that 80 these various movements may be imparted simultaneously.

85 The construction wherein the height of the discharge end of the conveyer may be adjusted is of considerable importance due to the fact that the size of the furnace door is necessarily restricted, and under certain circumstances may be too small to permit the desired vertical range of movement of the discharge end of the conveyer by shifting the peel either by swinging the peel about its transverse horizontal axis of movement as in Fig. 1, or by giving it a bodily vertical movement in the overhead crane type of machine shown in Fig. 3.

90 In Figs. 7 and 8 I have shown a distributing attachment which is particularly useful in obtaining an even distribution of the slagging material over the furnace floor. In this instance the outer end of the lower conveyer arm 44 is provided with a head 80 having an opening or spout 81 at the bottom leading into a hopper-like member 82 of a rotary distributor having at the bottom horizontally disposed outlets 83. This rotary 100 distributor is mounted to rotate about a vertical axis, and it is driven in this case from the conveyer shaft 46, which is provided at its outer end with a bevel gear 84 meshing with a bevel gear 85 on a short shaft 105 having near its lower end a spur gear 86 engaging teeth 87 on the cylindrical wall of the upper part of the distributor member 82.

110 This rotary distributor as before stated, is of particular importance in slagging the bottom of the furnace, but when the banks are to be slagged, I prefer that the distributing part of the conveyer have the discharge opening arranged as shown in Fig. 5.

115 When the slagging machine is not in use, that part of the apparatus including the platform 34, the conveyers and driving mechanisms, and in fact, all parts not forming a part of the charging machine *per se* 120 is deposited as a unit on any suitable support and at a point such as not to interfere with the operation of the charging machine, but when it is desired to slag the furnace, the slagging unit is picked up by the peel 130

and attached thereto and to the peel housing. To do this the forward end of the peel is inserted in a flanged groove of a casting 88 secured to the under side of the conveyer

5 arm 36, and it is locked thereto by the longitudinally extending bolt in precisely the same manner that the forward end of the peel is ordinarily attached to the box adapted to contain the charging material. Additionally in this case the platform is secured to the peel housing 27 by a clamp 89, and if desired, the end of the arm 36 next to the platform may be provided with a fork or yoke 90 adapted to rest on the peel so as to 10 form a support about midway between the casting 88 to which the forward end of the peel is attached and the clamp 89.

When the slagging part of the apparatus is attached in this manner to the peel and 20 its housing, there is formed a complete slagging unit which may be moved about from furnace to furnace and manipulated so as to slag the different furnaces. It will be understood that by horizontally swinging the distributing part of the conveyer, by raising or 25 lowering the discharge end when desired, and by moving the peel in and out, any part of the interior of the furnace to be slagged can be reached by the discharge end, the 30 range of movement being indicated partially in Fig. 3, where some positions of the distributing part of the conveyer are indicated by dotted lines.

It will be understood that this machine is 35 manipulated and all movements of all parts thereof are controlled from the outside of the furnace by an operator standing on the platform of the machine, or at the operator's station. To avoid confusion, the switches 40 and controllers for the several motors are not shown as they may have any suitable construction and arrangement to enable the motors to be started, stopped, operated at different speeds, and reversed where reversing 45 motors are used, in the most convenient manner.

This machine has all the advantages of that shown in the prior application in the way of accomplishing the slagging mechanically rather than by hand and in such 50 a manner that the material is distributed uniformly and accurately in a short space of time so as to effect a saving of material, time and labor, and in addition, has the advantage of a greater range of movement of 55 the discharge end of the distributing member, and numerous constructional advantages which improve the operation, strength and durability of the machine.

60 While I have shown the preferred construction utilized with two forms of a furnace charging machine, it will be understood that changes may be made in details and in the instrumentalities for carrying 65 out the principle of my invention, and I aim

in my claims to cover all modifications which do not involve a departure from the spirit and scope of my invention in its broadest aspects.

Having described my invention, I claim: 70

1. In an apparatus for slagging furnaces, supporting mechanism by which the apparatus may be moved about exteriorly of a furnace, conveying means for slagging material carried by said mechanism and adapted to be extended from the exterior to the interior of a furnace and including a distributing part adapted to be moved vertically with respect to a second part which supports it and which is adapted to be extended into the furnace. 75

2. In a furnace slagging machine, mechanism for conveying to and distributing slagging material on the interior of a furnace including a portion adapted to be extended into the furnace through the furnace door, and a distributing portion at the inner end of the first named portion, said distributing portion being mounted for swinging movement vertically relative to 80 the first named portion which supports it. 85

3. In an apparatus for slagging furnaces, conveying means for slagging material including a portion designed to be inserted in a furnace, and a distributing portion connected thereto for swinging movement about a substantially vertical axis and for swinging movement about a substantially horizontal axis. 90

4. In an apparatus for slagging furnaces, 100 a hollow conveying arm with means for conveying material therethrough and adapted to be extended into a furnace from the exterior thereof, and a second hollow arm with means for conveying material therethrough, connected to the first named arm so that its discharge end may be raised or lowered with respect thereto. 105

5. In apparatus for slagging furnaces, a hollow conveyer arm with means for conveying material therethrough designed to be extended into a furnace from the exterior thereof, and a distributor member including a hollow arm with means for conveying material therethrough connected to the 110 first named arm to swing horizontally and vertically with respect thereto. 115

6. In apparatus for slagging furnaces, a hollow conveyer arm adapted to be extended into a furnace from the exterior thereof, 120 a second hollow arm connected thereto to swing horizontally and vertically, means extending through said arms to convey material along the same, said conveying means being connected adjacent the point where the arms are movably connected together. 125

7. In an apparatus for slagging furnaces, a hollow conveyer arm adapted to be extended into a furnace from the exterior thereof, 130 a second hollow arm connected 135

thereto and movable horizontally and vertically with respect thereto, a screw conveyer extending through each of said arms, and means by which the conveyer in the 5 first named arm drives the conveyer in the second named arm.

8. In apparatus for slagging furnaces, a tubular conveyer arm adapted to be extended into a furnace and to be supported exteriorly thereof, a second conveyer arm connected to the first and adapted to receive slagging material therefrom, said second arm being pivotally connected to the first named arm to swing vertically about a substantially horizontal axis, and means operable 10 from the exterior of the furnace for swinging the arm.

9. In furnace slagging apparatus, a hollow conveyer arm adapted to be extended into the furnace and to be supported exteriorly thereof, a second hollow conveyer arm connected to the first to swing horizontally and vertically, and means operable from the exterior of the furnace for swinging said second arm horizontally and for swinging it vertically with reference to the first named arm.

10. In apparatus for slagging furnaces, a conveyer for slagging material including an arm adapted to be inserted in the furnace door and a second or distributing arm connected thereto to swing horizontally and vertically, conveying means extending along both arms and connected together so that one 30 will drive the other, the conveying means for the second arm comprising jointed parts with the center of movement located at a definite position with respect to the axis of vertical swinging movement of said second arm.

11. In apparatus for slagging furnaces, a conveyer for slagging material including an arm adapted to be inserted in the furnace door and a second or distributing arm connected thereto to swing horizontally and vertically, conveying means extending along both arms and connected together so that one will drive the other, the conveying means for the second arm comprising jointed 45 parts with the center of movement located at a definite position with respect to the axis of vertical swinging movement of said second arm, and means operable from the exterior of the furnace for controlling the movements of said second arm and for operating the conveying means for both arms.

12. In an apparatus for slagging furnaces, conveying and distributing means for slagging material comprising two members, one 60 the distributing part connected to the other for swinging movement horizontally and vertically, and means movable about on the exterior of the furnace and detachably connected to said conveying and distributing 85 means to support the same.

13. In an apparatus for slagging furnaces, conveying and distributing means for slagging material comprising two members, one the distributing part connected to the other for swinging movement horizontally and vertically, means movable about on the exterior of the furnace for supporting said conveying and distributing means and including an arm to which the conveying and distributing means is detachably connected. 75

14. In an apparatus for slagging furnaces, conveying and distributing means for slagging material comprising two members, one the distributing part connected to the other for swinging movement horizontally and vertically, and means for supporting the conveying and distributing means including a supporting device movable vertically and laterally on the exterior of the furnace. 80

15. In apparatus for slagging furnaces, 85 a hollow conveyer arm adapted to be inserted in the door of a furnace, a second arm movably connected thereto, means for conveying slagging material through both arms, and a rotary distributer at the discharge 90 end of the second arm.

16. In apparatus for slagging furnaces, a pair of jointed hollow arms including a distributing arm connected to swing with reference to the other arm, a rotary distributer at the free end of the distributer arm, means extending through both arms and connected together for feeding material through said arms, and likewise connected to said distributer to rotate the same. 95

17. In a slagging apparatus, a pair of hollow arms, one adapted to be extended into a furnace, and a second connected to the first to swing about in the furnace with reference to the first named arm, means extending through both arms and connected together adjacent the axis of movement of the second arm to convey material through said arms, and means extending along said second arm and separate from the conveying 105 means for swinging the second arm relative to the first. 110

18. In an apparatus for slagging furnaces, a pair of hollow conveyer arms including an arm adapted to be extended into a furnace, and a distributing arm connected thereto for swinging movement, screw conveyers in both arms, shafts extending through the arms and connected together at the axis of movement of the second arm for 115 operating the screw conveyers, and a shaft extending parallel to and alongside the shaft of the first named arm for swinging the second arm relative to the first. 120

19. In an apparatus for slagging furnaces, 125 a pair of hollow conveyer arms including an arm adapted to be extended into a furnace and a distributing arm connected thereto for swinging movement, screw conveyers in both arms, shafts extending through the arms and 130

connected together adjacent the axis of movement of the second arm for operating the screw conveyers, means extending along the first named arm for swinging the second arm relative to the first, the connection between the shafts for driving the two screw conveyers permitting the second arm to swing horizontally with reference to the first, and the shaft operating the conveyer in the second arm being composed of jointed parts which enable said second arm to swing vertically with reference to the first arm.

5 In testimony whereof I hereunto affix my signature.

EARL W. CLARK.
